UNITED STATES PATENT OFFICE.

SVEN TIDEMAN, OF COLUMBUS, OHIO.

CHRONOMETER-ESCAPEMENT.

1,336,263.

Specification of Letters Patent. Patented Apr. 6, 1920.

Application filed May 20, 1919. Serial No. 298,437.

To all whom it may concern:

Be it known that I, SVEN TIDEMAN, a subject of the King of Sweden, and a resident of Columbus, in the county of Franklin and State of Ohio, have invented a new and Improved Chronometer-Escapement, of which the following is a full, clear, and exact description.

The object of the invention is to provide a new and improved chronometer escapement arranged to prevent interference with the free oscillating movement of the balance wheel by the action of the driving train of gear wheels connected with the escapement wheel. Another object is to impart only a forward impulse to the balance wheel at each gyration. Another object is to impart the impulse to the balance wheel at the rim thereof thus relieving the pivot of the balance wheel of undue strain and thereby reducing friction to a minimum. Another object is to govern the force of the impulse given to the balance wheel to insure a definite speed of motion.

With these and other objects in view, the invention consists of certain novel features of construction as hereinafter shown and described and then specifically pointed out in the claims.

A practical embodiment of the invention is represented in the accompanying drawings forming a part of this specification, in which similar characters of reference indicate corresponding parts in all the views.

Figure 1 is an enlarged plan view of the improved chronometer escapement;

Fig. 2 is a side elevation of the same;

Fig. 3 is a plan view of a modified form of the chronometer escapement provided with a special driver;

Fig. 4 is a side elevation of the same;

Fig. 5 is a plan view of another modified form of the chronometer escapement;

Fig. 6 is a side elevation of the same;

Fig. 7 is a plan view of another modified form of chronometer escapement;

Fig. 8 is a side elevation of the same;

Fig. 9 is a plan view of another modified form of the chronometer escapement;

Fig. 10 is a side elevation of the same;

Fig. 11 is a plan view of another modified form of the chronometer escapement; and

Fig. 12 is a side elevation of the same.

The chronometer escapement illustrated in Figs. 1 and 2 comprises an escapement wheel 20 arranged to give impulses in the

usual manner to the pallets 21 and 22 of an escapement lever or anchor 23 provided with an arm 24 in which is secured by a set screw 25 or other fastening means the outer end 60 of a spring 26 secured at its inner end to the hub 27 of the balance wheel 28. The anchor arm 24 has a limited movement between two guide pins 30 and 31 attached to the framework of the chronometer. By the 65 arrangement described impulses given by the escapement wheel 20 to the anchor 23 are transmitted by the latter in a forward direction to the spring 26 of the balance wheel 28 thus causing the latter to oscillate. 70 It will be noticed that as the swinging movement given to the anchor arm 24 is limited between the pins 30 and 31, the balance wheel 28 is free to swing without the least interference by the actuating parts. 75

In the modified form shown in Figs. 3 and 4, the escapement wheel 40 imparts impulses by the pallets 41 and 42 to the anchor 43 provided with a pin 44 connected with one end of a spring 45 attached at its 80 other end to a pin 46 mounted on the balance wheel 47. Use is made of a driver 50 operating in conjunction with the anchor 43 and the balance wheel 47, and for this purpose the driver 50 comprises a staff 51 85 journaled in the framework of the chronometer and provided with a segmental gear wheel 52 adapted to coact with a segmental gear wheel 53 formed on a tail-piece 54 of the anchor 43. A spring 55 has its inner end 90 attached to the staff 51 and the outer end of this spring is fastened to a pin 56 carried on the framework of the chronometer. On the staff 51 is secured a plate 57 provided with a stud 58 adapted to coact with 95 a stud 59 projecting radially from the peripheral face of the balance wheel 47. The plate 57 is provided with a tailpiece 60 oscillating between stop pins 61 and 62 attached to the framework of the chronometer. 100 The plate 57 is provided on opposite sides with banking pins 65, 66 adapted to coact with the stud 59 to prevent the balance wheel 47 from describing more than two revolutions in a single gyration. 105

In the position shown in Fig. 3, the balance wheel 47 by its pull on the spring 45 holds the anchor 43 locked in the escapement wheel 40 by the pallet 42 with the driver plate 57 seated against the stop pin 61. 110 Presuming that the balance wheel 47 moves in the direction indicated by the arrow in

Fig. 3, then the stud 59 moves eventually into alignment with the anchor tail 54 whereby the spring 55 is released and comes into action thereby moving the driver 50 and by it the anchor in the direction indicated by the arrow at the driver 50. This movement causes the pallet 42 to move out of locking engagement with the escapement wheel 40, and hence the latter is rotated whereby the driving pin 58 in engagement with the stud 59 drives the balance wheel 47 forward until the tail 60 of the driver plate 57 moves against the stop pin 62. The several parts are now in the position to repeat the above described performance in the opposite direction whenever the balance wheel 47 swings in the inverse direction of its arrow, shown in Fig. 3. It is understood that one of the two banking pins 65 or 66 is in position to oppose the stud 59 should the balance wheel 47 attempt to describe more than two revolutions in a gyration. The spring 55 serves several purposes: first, it secures a central position of rest for the anchor 43 and with it the balance wheel 47 in relation to the escapement wheel 40; second, the spring 55 takes care of the friction on the anchor pivots and of the resistance in the release of the anchor 43 from the hold of the corresponding tooth of the escapement wheel 40 thus keeping the balance wheel 47 free of all interference from the driving train of gear wheels connected with the balance wheel including the anchor; third, the spring 55 aids the impulse by overcoming the inertia of the anchor 43 and it relieves the escapement wheel 40 from this burden; fourth, the spring 55 imparts a definite speed to the anchor 43 synchronous to that of the balance wheel 47 thus insuring pressure at the impulse proportional to the lag of the balance wheel; fifth, the action of the spring 55 ceases with the impulse, that is, when the anchor 43 strikes the guard pin thus leaving the rate of the balance wheel 47 undisturbed as governed by the balance spring 45. The driver 50 constitutes essentially a safety device and its functions are fourfold: first, it insures the effectiveness of the force applied by delivering a direct stroke to the balance wheel 47 at the peripheral face thereof with a view to cause the least friction on its pivots; second, the driver prevents the balance wheel 47 from getting a chance of skipping by forcing the balance wheel so far forward, before the corresponding pallet 41 or 42 can leave the corresponding tooth of the escapement wheel 40 and by the pull of the balance spring 45 the anchor 43 is held safely in locked position when the next following tooth of the escapement wheel 40 engages the corresponding pallet; third, the driver 50 makes the movement self-starting by allowing the anchor 43 to be set as far

from the center of the escapement wheel 40 as will permit of locking; and, fourth, the driver 50 prevents the balance wheel 47 from overstraining the balance spring 45 in cases of external disturbances by limiting through the banking pins 65, 66 and the stud 59 the possible oscillation to two revolutions. It is understood that when force is applied to the balance wheel 47 near its center the major part of the pressure falls on the pivots. This has heretofore been the practice, but in my arrangement the force is applied to the balance wheel 47 outside the peripheral face of the rim of the balance wheel and hence the weight of its mass, its inertia, virtually constitutes a frictionless fulcrum which takes up the major part of the pressure.

In the modified form shown in Figs. 5 and 6, practically the same construction is disclosed as the one illustrated in Figs. 3 and 4 and above described. This design is more especially for use in pocket chronometers and it comprises an escapement wheel 70 coacting with the pallets 71 and 72 of an anchor 73 having a pin 74 connected with the outer end of a spring 75 attached at its inner end to the balance wheel 76. The driver 80 in this case is provided with a staff 81 carrying a tooth 82 adapted to engage the forked end 83 of a tailpiece 84 forming part of the anchor 73 and carrying the pin 74 above mentioned. The plate 85 of the driver 80 is provided with a pin 86 coacting with a stud 87 extending radially from the peripheral face of the balance wheel 76. The tailpiece 88 of the plate 85 oscillates between stop pins 89, 90, and the plate is provided with banking pins 91 and 92 coacting with the stud 87, as above explained, relative to the banking pins 65 and 66 and the stud 59. A spring 95 is secured at its outer end to a post 96 attached to the framework of the chronometer and the inner end of the spring is fastened to the staff 81. The operation in this case is the same as above described in reference to the construction disclosed in Figs. 3 and 4, and hence further description of the same is not deemed necessary. In the several constructions disclosed in Figs. 1, 2, 3, 4, 5 and 6, the axes of the balance wheel and the anchor coincide.

In the modified form shown in Figs. 7 and 8, the escapement wheel 100 acts on the pallets 101 and 102 of the anchor 103 pivoted at 104 in the framework of the chronometer. The anchor 103 in this case is approximately of S-shape and is provided with a pin 105 to which is secured the outer end of a spring 106 connected at its inner end centrally to the balance wheel 107. The anchor 103 is provided with a segmental gear wheel 108 coacting with a segmental gear wheel 109 secured on the staff 110 of the driver 111. The driver 111 is provided

with a plate 112 carrying a pin 113 coacting with a stud 114 projecting radially from the balance wheel 107. Instead of banking pins, the plate 112 is provided with arms 115, 116 coacting with a pin 117 depending from the balance wheel 107. The staff 110 is connected with the inner end of a spring 120 connected at its outer end to a pin 121 attached to the framework of the chronometer. The action in this case is the same as above described in reference to the construction disclosed in Figs. 3 and 4, the only difference being that the arms 115 and 116 limit the movement of the balance wheel 107 by moving into the path of the pin 117 to prevent the balance from describing more than two revolutions in a gyration.

In the modified form shown in Figs. 9 and 10, the escapement wheel 130 imparts impulses to the pallets 131 and 132 of an anchor 133 having its staff 134 connected with the inner end of a spring 135 attached at its outer end to a pin 136 mounted on the framework of the chronometer. This spring 135 corresponds in action to the spring 55 described above and illustrated in Figs. 3 and 4. The tail 137 of the anchor 133 oscillates between the stop pins 138 and 139 attached to the framework of the chronometer. The anchor 133 is provided with a pin 140 connected with one end of the balance spring 141 connected at its other end to a pin 142 depending from the balance wheel 143 having its staff 144 coinciding with the staff 134 of the anchor 133. The action of the several parts is practically the same as the one described in reference to the construction disclosed in Figs. 3 and 4 with the only differences that the driver 50 is dispensed with and the spring 135 is directly connected with the anchor 133.

In the modified form shown in Figs. 11 and 12, the escapement wheel 150 imparts impulses to the pallets 151, 152 of the anchor 153 provided with a tailpiece 154 oscillating between the stop pins 155, 156 attached to the framework of the chronometer. The staff 160 of the anchor 153 is connected with the inner end of the spring 161 having its outer end attached to a pin 162 secured to the framework of the chronometer. This spring 161 has the same functions as the springs 55 and 135 above mentioned so that further description of the same is not deemed necessary. The anchor 153 is provided with a depending pin 170 to which is attached one end of a spring 171 having its other end 172 attached to the hub 173 of a balance wheel 174. By the arrangement described the balance wheel 174 is suspended by the spring 171 from the anchor 153 but the action is the same as above described so that further description of the same is not deemed necessary.

65 In the devices shown in Figs. 9, 10, 11

and 12, the axes of the balance wheels 143 and 174 coincide with the axes of the anchors 133 and 153, respectively.

From the foregoing it will be seen that interference with the free oscillating movement of the balance wheel by the action of the driving train of gear wheels is completely prevented. Furthermore, only a forward impulse is given to the balance wheel at each gyration and the impulse is imparted to the balance wheel at the rim thereof thus relieving the pivot of the balance wheel of undue strain and thereby reducing the friction at the pivot to a minimum. It will also be seen that by the arrangement described, the force of the impulse given to the balance wheel is governed by the actions of the spring-pressed driver which provides a definite speed of motion proportional to the proper speed of the balance wheel at the time the latter comes under its influence.

If any cause reduces the amplitude of the balance wheel, its speed when passing the central position is also reduced thereby subjecting it to a harder application of the driving force by increasing the time and violence thereof, whereas an increase in amplitude and speed of the balance wheel beyond its proper limit reduces the application of the force until, when the anchor and driver fail to catch up with it, the impulse is reduced to *nil*, and beyond which point its effect becomes of a reversed direction. Furthermore, this construction does not require a close adjustment of the pivot holes to the pivots of the balance wheel and which adjustment usually interferes with the lubricating effect of the oil so well known to watchmakers.

It is understood that each of the springs 95, 111, 135 and 161 has the same functions as the ones described above relative to the spring 55, and hence further description of the same is not deemed necessary.

Having thus described my invention, I claim as new and desire to secure by Letters Patent:—

1. In an escapement, an escapement wheel, an anchor in operative relation with the said escapement wheel and provided with a tail piece, an oscillating driver, an operative connection between said tailpiece and driver, tensioning means connected with the said driver, a balance wheel, said driver adapted to move into operative relation to said balance wheel, and means for limiting the oscillating movement of the driver.

2. In an escapement, an escapement wheel, an anchor in operative relation with the said escapement wheel and provided with a tail piece, an oscillating driver, an operative connection between said tailpiece and driver, tensioning means connected with the said driver, a balance wheel, said driver adapted to move into operative relation to said bal-

ance wheel, means for limiting the oscillating movement of the driver, and means on the said driver adapted to move into stopping relation to the said balance wheel.

- 5 3. In an escapement, an escapement wheel, an anchor in operative relation with the said escapement wheel and provided with a tailpiece having a segmental gear wheel, an oscillating driver having a segmental gear wheel in mesh with the said tailpiece gear wheel, a spring fixed at one end and connected with the said driver, a balance wheel having a stud, and a stud on the said driver adapted to move into operative relation to the stud on the balance and guard pins to limit the oscillating movement of the driver.
- 10 4. In an escapement, an escapement wheel, an anchor in operative relation with the said escapement wheel and provided with a tailpiece having a segmental gear wheel, an oscillating driver having a segmental gear wheel in mesh with the said tailpiece gear wheel, a spring fixed at one end and connected with the said driver, a balance wheel having a stud, a stud on the said driver adapted to move into operative relation to the stud on the balance and guard

pins to limit the oscillating movement of the driver, and banking pins on the said driver and adapted to move into stopping relation to the said balance wheel std.

- 5 5. In an escapement, a balance wheel, and means imparting impulses to the balance wheel at the rim thereof.

6. In an escapement, a balance wheel provided on its rim with a stud, and driving means adapted to engage the said stud.

7. In an escapement, an escapement wheel, an anchor having pallets coacting with the said escapement wheel, a balance wheel, a spring connecting the anchor with the balance wheel, and a driver oscillated from the said anchor and having means imparting impulses to the balance wheel, and a spring connected with the said driver.

8. In an escapement, an escapement wheel, an anchor having pallets coacting with the said escapement wheel, a balance wheel, a spring connecting the anchor with the balance wheel, a driver oscillated from the said anchor and having means imparting impulses to the balance wheel, and a spring fixed at one end and having its other end connected with the driver.

SVEN TIDEMAN.
